UNITED STATES PATENT OFFICE.

JOSEPH H. HUMPHREY AND EDWARD ZOLA, OF ST. LOUIS, MISSOURI; SAID ZOLA
ASSIGNOR TO SAID HUMPHREY.

TIME-CONTROLLED SWITCH-OPERATING DEVICE.

Application filed November 14, 1921. Serial No. 514,937.

To all whom it may concern:

Be it known that we, JOSEPH H. HUMPHREY and EDWARD ZOLA, citizens of the United States, and residents of the city of St. Louis and State of Missouri, have invented certain new and useful Improvements in Time-Controlled Switch-Operating Devices, of which the following is a specification, containing a full, clear, and exact description, reference being had to the accompanying drawings, forming a part hereof.

Our invention relates to certain new and useful improvements in time controlled switch operating devices, which is so arranged that it will operate the lighting switch of an automobile at a predetermined time.

A further object is to construct a time controlled switch operating device for automobiles which can be set so that the lights will be automatically turned on at the hour designated by law.

In the drawings,

Fig. 1 is a front elevation of our device mounted on the instrument board of an automobile.

Fig. 2 a front elevation of a clock with the time setting portion removed.

Fig. 3 a cross section taken on the line 3—3 of Fig. 1, showing the manner of making the various electrical connections.

Fig. 4 a side elevation with parts in section, showing the manner in which the lighting switch is operated.

Fig. 5 an enlarged fragmental section, showing the manner of forming the electrical connection to the time setting portion.

In the construction of our device we employ a clock 6. This clock is of ordinary construction, and therefore will not be described in detail. This clock is secured within a housing 7, which is provided with a flange 8 by means of which the housing is secured to the instrument board 9 of an automobile. The housing 7 has the portion 10 projecting forward from the flange 8. This projecting portion is provided with bayonet grooves 11, which receive pins 12, these pins being secured to the casing 13 of the clock. The casing 13 is further held against rotation by means of a set screw 14 which passes through the portion 10 and secures the clock against

jolting out of the bayonet joint. The clock is provided with the usual hands 15 and 16, 15 indicating the hour hand. The clock case 13 is provided with a grooved flange 17, the grooved portion extending or fitting over the projecting portion 10 of the housing 7. The flange 17 is provided with projecting ears 18, which are adapted to be bent over a ring 19 formed of insulating material. Secured to the ring 19 by means of screws 20 is a glass cover 21. The ring 19 is provided with an internal flange 22 which is recessed to receive a conductor ring 23. This conductor ring has integral formed contact brushes 24 and 25 which are spaced apart sufficiently to allow the hour hand 15 to pass through and make a slight contact. This contact, however, is not sufficiently strong to stop the operation of the clock. The ring 19 is movably held by means of the ears 18, so that it can be freely rotated and allow the contact brushes 24 and 25 which are carried thereby to be set at any point throughout the circumference of the dial. The ring 23 engages with the contact brush 26. This brush is formed of two strips of conducting material and is secured to the housing 7 but fully insulated therefrom by means of the insulation 27 and insulating washer 28. Secured to the brush 26 is a conductor 29. The opposite end of this conductor is secured to a binding post 30 mounted on the insulating plate 31. Secured to the binding post 30 is a conductor 32, which leads to the coil 33 of an electro-magnet. The coil 33 of the electro-magnet is connected to the coil 34 by means of a conductor 35, while the coil 34 is connected to the battery 36 by means of the conductor 37. Secured to the battery 36 is a conductor 38 which has its free end attached to and grounded in a binding post 39, this binding post being in turn secured to the housing 7. The flange 8 is provided with a downwardly projecting portion 40 through which extends the shank 41 of a switch. This switch is housed in an insulating block 42, and is so arranged that when the shank 41 is moved forward, the plate 43 will contact with the plates 44 and 45, and thus form an electrical circuit by means of the conductors 46 and 47, the conductor 46 leading to the switch 42. This switch being in turn connected to the battery 36 by means

of a conductor 49, the conductor 47 leading to the lamp 50. From this lamp a return conductor 51 leads to the battery.

Our object in interposing the switch 48 in the lamp circuit is for the reason that the hour hand will pass the contact brushes 34 and 35 twice in twenty-four hours, and it is to obviate the possibility of the lights being turned on when not wanted or while the machine is in the garage that this switch is installed. The shank 41 projects through the switch housing 42 (see Fig. 4,) and is for the purpose of permitting the rod 52 to contact therewith. The rod 52 is supported by means of the bracket 53. The armature 54 of the electro-magnet extends downward and is provided with an opening 55 which passes over the bar or rod 52. This bar has mounted thereon washers 56 which are placed on either side of the armature 54 and are retained in position by means of pins 57, so that when the armature is operated in either direction, it will come in contact with one of the washers 56 and move the bar 52 forward or backward.

The operation of our device is as follows:

After the proper connections have been made the device is set for lighting. For instance, the law requires the proper lights 30 to be turned on at five o'clock. The insulating ring 19 is adjusted so that the contact brushes 24 and 25 will assume the position shown in Fig. 1, that is, directly opposite the numeral five on the clock. The switch 48 is then turned on. Then as the clock runs, the hand 15 will contact with the brushes 24 and 25. This will complete the circuit through the electro-magnets by means of the conductors 37 and 38 leading 35 from the battery, the conductor 29 leading from the brushes 26 and the conductor ring 23, the return circuit being made through the housing 7, the casing 13 being in direct contact with this housing—the electric circuit necessarily passes through the works of the clock and through the hand 15, so that a complete circuit is established. This energizes the coils 33 and 34 of the electro-magnet pulling the armature 54 40 forward. This in turn imparts movement to the rod 52 which contacts with the end of the shank 41, and operates the light

switch. We may if desired leave the light circuit intact, that is, operate it by means of the shank 41 only, and place the switch 48 in the electro-magnet circuit without departing from the spirit of our invention.

By the use of our device any clock furnished with an automobile can be utilized, the only change necessary being to install the housing 7 with its several parts and to mount the glass or crystal 28 on the time setting portion or insulating ring 19. Thus it will be seen that the device is comparatively cheap in construction and does not necessitate a great deal of reconstruction for installing the same in an automobile.

Having fully described our invention, what we claim is:

1. A time controlled switch operating device comprising a housing, a ring of insulating material rotatably carried thereby, a conductor ring having integrally formed contact brushes secured to said insulated ring, a clock located in said housing and adapted to have one of its hands contact with said brushes, an electro-magnet adapted to be energized when said contact is made, and a switch adapted to be closed by said magnet when the same is energized.

2. A time controlled switch operating device comprising a housing, a ring of insulating material rotatably carried thereby, a conductor ring having integrally formed contact brushes secured to said insulated ring, a clock located in said housing and adapted to have one of its hands contact with said brushes, a contact brush carried by and insulated from said housing, said brush contacting with the conductor ring, an electro-magnet, a connection between the electro-magnet and last mentioned contact brush, electric conductors secured to the contact brush and electric-magnet whereby the same is energized when contact is made between the hand and the brushes carried by the insulating ring, and a switch adapted to be closed by said electro-magnet when the same is energized, and manually operated to open the same.

In testimony whereof, we have signed our names to this specification.

JOSEPH H. HUMPHREY.
EDWARD ZOLA.
